[57] CLAIM

The ornamental design for a combined attachable bottle nipple and pacifier pouch, as shown and described.

DESCRIPTION

FIG. 1 is a top front perspective view of a combined attachable bottle nipple and pacifier pouch showing my new design; and,

FIG. 2 is a bottom rear perspective view thereof. The broken line showing a conventional baby bottle in FIGS. 1 and 2 are for illustrative purposes only and forms no part of the claimed design.

Fig. 1.

Fig. 2.
